CLAIM

The ornamental design for a stethoscope cover, as shown and described.

DESCRIPTION

FIG. 1 is a top plan view of the stethoscope cover.

FIG. 2 is a bottom side perspective view of the stethoscope cover.

FIG. 3 is a side elevation view of the stethoscope cover; and, FIG. 4 is a bottom plan perspective view of the stethoscope cover.

The broken lines depict portions of the stethoscope cover that form no part of the claimed design.
